AUXILIARY SWITCH FOR ELECTROMAGNETICALLY OPERATED DEVICES

Lynn H. Matthias, Fox Point, Wis., assignor to
 Allen-Bradley Company, Milwaukee, Wis., a
 corporation of Wisconsin

Application February 10, 1940, Serial No. 318,292

3 Claims. (Cl. 200—87)

This invention relates to an auxiliary switch for an electromagnetically operated device as disclosed in the application of Gustav O. Wilms and Albert J. Dawe for "Electromagnetically operated devices," filed January 22, 1940, Serial Number 315,040 and assigned to the assignee of this application, which is the Allen-Bradley Company.

In the operation of an electromagnetic device where actuation of the movable element of the electromagnet to the closed position is accomplished by energizing the magnetic circuit by means of A. C. or D. C. current and then maintaining the movable magnetic element in the closed position by means of residual magnetism derived from energization of the magnetic circuit during the operation of closing, the successful performance is largely dependent upon being able to de-energize the device at the proper instant. The object of this invention is to disclose a preferred arrangement for de-energizing the closing magnetizing circuit so as to obtain a more reliable magnetic lock for the electromagnetic device.

A further object of this invention is to secure a simple and satisfactory auxiliary switching device that is actuated by the movement of the movable member of an electromagnet and capable of obtaining and maintaining a very accurate relationship between the movement of the movable member of the electromagnet and the actuation of the switch.

A still further object of this invention is the provision of an auxiliary switching device actuated by the movable member of an electromagnet and which switching device may be easily adjusted as to its movement and thereafter remain in such adjustment.

These objects are accomplished by a unique arrangement and construction of parts as described below and on the attached drawings forming a part of this disclosure.

Referring to the drawings:

Figure 1 is a front view of an electromagnetically operated device with an attached auxiliary switch and shown in the unoperated position;

Figure 2 is a side view of the device shown in Figure 1 with the auxiliary switch shown in section along lines 2—2 in Figure 1;

Figure 3 is a side view of the device shown in Figure 1 in the operated position and with the auxiliary switch shown in section along lines 3—3 in Figure 1;

Figure 4 is an enlarged partially sectioned view 55

of the auxiliary switch taken along the lines 4—4 in Figure 2;

Figure 5 is a side view of an alternate form of the invention shown in the unoperated position with the auxiliary switch shown in a partially sectional view along the lines 5—5 in Figure 6; and

Figure 6 is a front view of the alternate form of the invention shown in Figure 5.

There are two specific disclosures of the invention shown that have proven to be highly satisfactory and are illustrative of the generic invention. Figures 1 and 6 show the two preferred forms and are explained in detail below.

Figures 1, 2, 3 and 4 show the form of auxiliary switch that has proven to be desirable when used with a solenoid type electromagnetic device in which the solenoid core is biased to the unoperated position essentially by gravity and it is undesirable to have the auxiliary switch effect the bias materially. This is particularly important on electromagnetically operated devices of comparatively small size. Figures 5 and 6 show the alternate form of auxiliary switch that is more suitable for use on larger electromagnetically operated devices where the biasing action of the solenoid is sufficient to warrant some decrease due to the counter-biasing action of its auxiliary switch. Both forms of this device will be described simultaneously with reference to corresponding parts of the two types by separate, but related numerals—the second form differing from the first by the suffix one hundred i. e. first form 1, second form 101; or first form 2, second form 102, etc.

The electromagnetic device 2 or 102 and the auxiliary switch 6 or 106 are rigidly mounted together by means of the mounting structure 1 or 101. The electromagnetic device 2 or 102 consists of a fieldpiece 3 or 103, armature 4 or 104 and coil 5 or 105. The auxiliary switch 6 or 106 consists of an insulating moulding 7 or 107 spaced from the mounting structure 1 or 101 by means of a sheet of insulation 8 or 108 both being held rigidly in place by means of mounting screws 9 or 109. This switch has mounted therein a stationary contact terminal 10 or 110 with an attached stationary contact 11 or 111, another terminal 12 or 112 having attached thereto by means of a flat metallic spring 14 or 114 a movable silver contact 13 or 113 arranged to engage or disengage the stationary silver contact 11 or 111. The switch actuator 16 or 116 is pivotally mounted on base 7 or 107 by means of pivot 15 or 115 and arranged to engage or disengage the

flat spring 14 or 114 by means of the presser foot 28 or 128 to actuate the single-break auxiliary switch.

The auxiliary switch actuating lever 16 or 116 is coupled to the armature 4 or 104 by means of coupling device 17 or 117 so that the contacts of the auxiliary switch are closed when the armature is in the unoperated position and open when in the operated position. The coupling device 17 or 117 is so adjusted that the opening of the contacts occurs slightly before the pole faces 38 or 138 of the armature and fieldpiece engage. The detailed description thus far given relates to both forms disclosed and constitutes those parts of the device per se that have a common function. The coupling devices 17 or 117 are different in construction and operation and will be described in detail separately.

The coupling device 17 used in the first form and shown in Figures 1, 2 and 3 consists of a coupling pin 20 attached to a flat plate 18 that is rigidly mounted to the armature 4 by means of rivet 19. The auxiliary switch actuating lever 16 loosely engages the pin 20 by means of the shoulder of the hole 27 in the lever 16. A ball pointed adjusting screw 24 threaded in the lever 16 maintains a spaced relation between the plate 18 and the lever 16 and is adjustable and can be locked by means of lock-nut 25. The lever 16 is maintained in the coupled position by means of coil spring 21 that fits in recess 26 on lever 16 and held in place by cup washer 22 and cotter pin 23. There is thus provided an extremely flexible coupling between the armature and the auxiliary switch actuating lever that introduces very little strain or friction on the armature, does not materially alter the bias of the armature, and yet, is capable of very accurate and reliable adjustment of the point of operation of the auxiliary switch.

In the second form shown in Figures 5 and 6 the auxiliary switch actuating lever 116 has a heel 141 that engages a biasing spring 139 that fits in the recess 140 of switch base 107. The lever is thus biased to the operated position of the electro-magnetic device and against the biasing action of the armature 104. The lever engages the armature by means of the ball pointed adjusting screw 124 which is locked in place by means of lock-nut 125. There is thus provided a very simple coupling device between the armature and auxiliary switch actuating lever that introduces very little strain or friction on the armature and is capable of very accurate and reliable adjustment of the point of operation of the auxiliary switch.

The operation of the two forms shown in Figures 1 and 6 are similar. In the particular form disclosed, the fieldpiece 3 or 103 is constructed of laminations of steel having low retentivity and low coercive force and the armature 4 or 104 is constructed of laminations of steel having high retentivity and high coercive force. With the armature 4 or 104 in the disengaged position as shown, the silver contacts of the auxiliary switch 6 or 106 are in the closed position. In order to operate the electro-magnetic device 2 or 102 to cause the pole faces 38 or 138 of the armature 4 or 104 and fieldpiece 3 or 103 to engage, a sufficient source of A. C. power is connected to terminals 29 and 30 or 129 and 130 of the "close" switch 31 or 131 is operated completing a circuit from terminal 29 or 129, conductor 46 or 146, contacts of "close" switch 31 or 131, conductor 34 or 134, coil 5 or 105, conductor 33 or 133, contacts 75

of auxiliary switch 6 or 106 and conductor 32 or 132 to terminal 30 or 130. Thus a sufficient A. C. magnetizing force is developed in the coil 5 or 105 to cause the armature 4 or 104 to move toward the closed position (specifically shown for form one in Figure 3) and to open the contacts of the auxiliary switch 6 or 106 substantially at the time the armature 4 or 104 and fieldpiece 3 or 103 engage. If the energizing current is interrupted at a proper point on the A. C. power cycle, the residual flux in the magnetic circuit will be sufficient to hold the armature in the closed position against the bias of the armature. In the event that the residual flux is insufficient to maintain the armature in the closed position, the magnetizing circuit becomes reenergized as the armature moves toward the open position thus repeating the closing cycle. The operation of the auxiliary switch is very closely coordinated with the relative movement of the armature and fieldpiece. The operating lever of the auxiliary switch is adjusted so that the contacts open when the air gaps between the adjacent pole faces of the armature and fieldpiece are about 0.010 inch. With an accurate and reliable adjustment of this magnitude a very satisfactory and reliable closure of the armature is obtained.

In order to return the armature to the open position it is only necessary to energize the coil 5 or 105 with an A. C. magnetizing force just sufficient to reduce the residual magnetism to a value insufficient to maintain the armature in the closed position against its bias. This is accomplished as follows: with the "close" switch 31 or 131 open, a sufficient source of A. C. power is connected to terminals 43 and 47 or 143 and 147 and the "open" switch 44 or 144 is operated completing a circuit from terminal 43 or 143, conductor 42 or 142, contacts of "open" switch 44 or 144, conductor 45 or 145, conductor 34 or 134, coil 5 or 105, conductor 33 or 133 and conductor 48 or 148 to terminal 47 or 147.

The "close" switch 31 or 131 and "open" switch 44 or 144 should be arranged so that both cannot be closed together. This can be accomplished by means of a mechanical interlock or other suitable arrangement.

The mode of operation of the electromagnetic device given above contains no reference to the theoretical explanation of its operation. The application of Gustav O. Wilms and Albert J. Dawe, referred to above, is directed to an electromagnetic device of the types shown in Figures 1 and 6 and adequately explains the theory of operation of the device and various modifications that can be incorporated therein without departing from the inventive thought. Reference to the Wilms and Dawe application will aid greatly in acquiring a proper appreciation of the importance and value of this invention in improving the operation of the Wilms and Dawe Electromagnetic device.

In the specific devices shown the armature moves from the open position to the closed position in an exceedingly short period of time. The device when operated on 60 cycle A. C. current closes in approximately 1 cycle and the time interval for the armature to travel from the point of actuating the auxiliary switch to the closed position is approximately $\frac{1}{50}$ of a cycle. As the time required to extinguish an A. C. arc under proper conditions can be almost $\frac{1}{2}$ cycle, it is evident that the auxiliary switch actually interrupts the coil current after closure of the armature and fieldpiece. Any lag in motion of

the operating lever is also such that time delay in interruption of the coil current is obtained. It is highly desirable to operate this device so that actual de-energization of the coil occurs at or after closure of the magnetic circuit. The auxiliary switch is simple in construction and by the use of a single-break contact, using a small gap and electrodes that cause the arc to persist, an effective time delay is obtained.

In other words the coil current is interrupted after closure of the armature with the fieldpiece, and such closure of the armature is at or substantially at zero value of the coil current.

The resultant effect is a comparatively high value of magnetic flux in the closed magnetic circuit of armature and fieldpiece when the energizing current is cut off by the controlling switch. The electromagnet therefore remains in its closed position against the acting bias.

Electromagnetic devices of the type referred to herein are of compact and rugged construction and usually used in a wide variety of applications that demand reliable operation under adverse conditions. The electromagnetic device operates with tremendous force in a very short interval of time. It is, therefore, essential that the auxiliary switch be so arranged and constructed that objectionable rebound of parts be minimized, that wear of parts be proportioned so as to compensate in such manner that the operating characteristics are not impaired and that the structure be correspondingly compact and rugged.

While in accordance with the patent statutes I have disclosed details of two specific forms of my invention, and while certain of the claims are directed to the details of my preferred forms, it is to be understood that the principles disclosed are capable of much wider adaptation when used on electromagnetic devices generally. I desire, therefore, that the language of the claims be accorded the broadest reasonable construction, and that my invention shall be limited only by what is expressly stated therein and by the prior art.

I claim as my invention:

1. An electric switch for an electromagnet operable by alternating current, said electromagnet comprising a magnetic circuit including a fieldpiece, an energizing winding for said fieldpiece, and an armature biased from its closed position with the fieldpiece, said magnetic circuit with armature and fieldpiece closed capable of residual magnetism derived from energization of said winding by alternating current to provide a holding force sufficient to maintain said armature closed against said bias; said electric switch comprising a movable member having a portion extending into the path of movement of said armature, a spring for urging said member into contact with said armature so as to cause said member to move to follow the movement of said armature, a pair of normally closed separable contacts electrically connected to said coil for interrupting current flowing therethrough, said contacts being positioned so as to be engaged and opened by said movable member during inward travel of said armature only after a point is reached near to the closed position of said armature, and adjustable means for adjustably fixing the point in the inward travel of the armature at which said contacts are engaged and separated.

ture, and adjustable means for adjustably fixing the point in the inward travel of the armature at which said contacts are engaged and separated.

5. 2. An electric switch for an electromagnet operable by alternating current, said electromagnet comprising a magnetic circuit including a fieldpiece, an energizing winding for said fieldpiece, and an armature biased from its closed position with the field piece, said magnetic circuit with armature and fieldpiece closed capable of residual magnetism derived from energization of said winding by alternating current to provide a holding force sufficient to maintain said armature closed against said bias; said electric switch comprising a lever pivoted on a stationary support and having a follower arm extending into the path of movement of said armature and also having a contact actuating arm, a spring interposed between said stationary mounting and said lever for urging the follower arm of said lever toward said armature so as to cause said lever to follow the movement of said armature, a pair of normally closed separable contacts electrically connected to said coil for interrupting current flowing therethrough, said contacts being positioned so as to be engaged and opened by said contact actuating arm during inward travel of said armature only after a point is reached near to the closed position of said armature, and an adjusting finger interposed between said follower arm and said armature for adjustably fixing the point in the inward travel of said armature at which said contacts are engaged and separated.

3. An electric switch for an electromagnet operable by alternating current, said electromagnet comprising a magnetic circuit including a field piece, an energizing winding for said fieldpiece, and an armature biased from its closed position with the fieldpiece, said magnetic circuit with armature and fieldpiece closed capable of residual magnetism derived from energization of said winding by alternating current to provide a holding force sufficient to maintain said armature closed against said bias; said electric switch comprising a lever pivoted on a stationary support and having a follower arm extending into the path of movement of said armature and also having a contact actuating arm, an extension rigidly secured to said armature, a spring interposed between said extension and said follower arm for urging said follower arm toward said armature so as to cause said lever to follow the movement of said armature, a pair of normally closed separable contacts electrically connected to said coil for interrupting current flowing therethrough, said contacts being positioned so as to be engaged and opened by said contact actuating arm during inward travel of said armature only after a point is reached near to the closed position of said armature, and an adjusting finger interposed between said follower arm and said armature for adjustably fixing the point in the inward travel of said armature at which said contacts are engaged and separated.

LYNN H. MATTHIAS.
